BANDALORE TOY

George F. Scott, St. Petersburg, Fla.

Application April 25, 1952, Serial No. 19,467

Term of patent 14 years

(Cl. D34—15)

To all whom it may concern:

Be it known that I, George F. Scott, a citizen of the United States, residing at St. Petersburg, in the county of Pinellas and State of Florida, have invented a new, original, and ornamental Design for Bandalore Toy, of which the following is a specification, reference being had to the accompanying drawing, forming a part thereof.

Fig. 1 is a front elevation of a bandalore toy showing my new design.

Fig. 2 is an end view of the bandalore toy shown in Fig. 1.

The dotted lines of Fig. 1 are for illustrative purposes only.

I claim:

The ornamental design for a bandalore toy, as shown and described.

GEORGE F. SCOTT.
